COMPRESSOR CONSTRUCTION

Nathan C. Price, St. Helena, Calif., assignor to
Lockheed Aircraft Corporation, Burbank, Calif.

Application November 28, 1947, Serial No. 788,350

23 Claims. (Cl. 230—122)

1

This invention relates to compressors or blowers and has more particular reference to axial flow type compressors. It is a general object of the invention to provide an axial flow compressor characterized by a simple, inexpensive and extremely light weight rotor construction.

This application is a continuation-in-part of my co-pending application, Serial No. 583,152, filed March 16, 1945, which, in turn, is a division of my co-pending application, Serial No. 438,029, filed May 22, 1943, now Patent No. 2,468,461, issued April 26, 1949.

It is another object of the invention to provide an axial blower or compressor of the axial flow multiple blading row type which has an extremely light weight rotor that preserves its circularity and maintains adequate blade tip clearance even during high speed operation. The light weight rotor particularly adapts the compressor for use in aircraft power plants, and the like, where weight is an important consideration.

Another object of the invention is to provide a compressor of the class referred to characterized by a light weight rotor shell of thin metal effectively reinforced by internal hoops which carry the axially spaced rows of radially projecting blades to relieve the shell of the major loading. This form of rotor construction is well suited for mass production methods, is inexpensive, and results in a strong, dependable, light weight wheel or rotor.

Another object of the invention is to provide an axial flow compressor in which the rows of impeller blades in upstream and downstream relation to one another are slotted and have their interiors in communication with one another so that the pressure differential in the main passage of the blower causes air flow into the slots of the blades in one row and the discharge of air from the slots of the other row to increase the boundary layer flow over the surfaces of the blades thereby assuring efficient blade operation throughout the wide range of coefficients of lift that may be encountered as a result of variation in ambient air density and pressures at the first rows of diffuser vanes. The augmented boundary layer flow reduces the tendency of the boundary layer to separate from the blade surfaces and lessens the drag so that the main air flow follows the blade surfaces to greater angles of attack.

When the compressor is embodied in a power plant for propelling high altitude aircraft, it must, of necessity, operate at varying pressure altitudes and function at variable compression

2

ratios. In order to maintain substantially constant operative pressures within the combustion zone and gas turbine of the power plant, the first stage compressor is regulated to operate at lower speeds in the denser ambient air of low altitudes and to function at higher speeds in the low density ambient air of the higher altitudes. This variation of operating conditions requires that the impeller blades of the first stage compressor and, particularly, the first rows of such blades operate through a wide range of angles of attack relative to the entering air and with respect to the partially compressed air leaving the first rows of intermediate diffuser vanes, that is the initial rows of impellers must operate over a wide range of coefficients of lift. This range of coefficients of lift is greatly in excess of the range for efficient impeller operation and under certain conditions at low altitude the first rows of impeller vanes may operate under practically stalled conditions. The increased boundary layer flow obtained by the present invention brings about efficient vane or blade operation through the wide range of coefficients of lift.

It is a further object of the invention to provide an axial compressor of the class referred to in which the hollow rotor shell constitutes a common means of communication between the several hollow slotted blades with appropriate metering means being provided for the blades to assure the required or proper relationship between the volume of air flow through the slots of the spaced blading rows.

Other objectives and advantages of the invention will become apparent from the following detailed description of typical preferred embodiments, throughout which description reference is made to the accompanying drawings wherein:

Figure 1 is a fragmentary side elevation of a compressor of the invention with a portion broken away to illustrate the rotor and adjacent parts in cross section;

Figure 2 is an enlarged fragmentary sectional view of the compressor shell showing the blades in side elevation;

Figure 3 is a fragmentary sectional view taken as indicated by lines 3—3 of Figure 2;

Figures 4 and 5 are enlarged transverse sectional views of the blades of different rows;

Figure 6 is a fragmentary sectional view of another form of blade attachment; and

Figure 7 is a fragmentary perspective view of a blade and blade shank employed in the structure of Figure 6.

In the drawings the invention is illustrated

embodied in a blower or compressor for an internal combustion turbo power plant of the type disclosed in my co-pending application Serial No. 488,029. The compressor may be considered the first stage compressor arranged at the forward end of the power plant to receive the ram air and may be considered as driven by the turbine of the power plant through the medium of a suitable drive. However, it will be apparent that the features of the invention may well be embodied in compressors designed for other applications and installations.

The illustrated structure includes an elongate cylindrical housing 10 which may constitute the forward portion of the power plant casing and the case or shell of the compressor. The forward end of the housing 10 is open and provided with a grooved spigot 12 which constitutes the inlet of the compressor.

The blower or compressor includes a rotor arranged longitudinally and coaxially within the housing 10. The construction of the wheel or rotor is a feature of the invention. The improved rotor comprises a shell 20 preferably constructed of relatively thin sheet metal or the like. While the thickness of the sheet metal of the rotor shell will depend upon the overall size of the compressor, and upon other considerations, the thickness of the shell in most instances is between thirty-five and ninety one-thousandths of an inch. The rotor shell 20 is in the form of a truncated cone of rearwardly increasing diameter and may be fabricated from a thin metal tube spun or otherwise worked to the required shape. The compressor rotor further includes internal rings or hoop-like reinforcing and blade carrying elements. In the construction illustrated there is a plurality of axially spaced pairs of reinforcing rings 21 and 22 of angular cross section. The pairs of rings 21 and 22 are graduated or varied in diameter to conform to the tapering shell 20 and their axially extending flange parts are fixed to the internal surface of the shell by riveting, welding, brazing, or the like. As best illustrated in Figure 2 the hoops or rings of each pair are spaced apart axially of the rotor and are related to have their inwardly projecting circumferential flanges 13 in spaced generally parallel relation. The pairs of rings 21 and 22 are spaced longitudinally throughout the length of the shell 20 or at least throughout that portion of the shell which carries the impeller vanes. The rings 21 and 22 mount the impeller vanes as will be later described and their spacing is determined by the required spacing of the blading rows.

The rotor shell 20 constructed of the thin sheet metal and reinforced by the spaced internal hoops or rings 21 and 22, as just described, is light in weight and inexpensive to manufacture, and yet possesses ample strength and rigidity to maintain its circularity and the blade tip clearance during high speed operation.

I have shown the forward end of the rotor shell 20 provided with a forwardly projecting hollow spindle 48 rotatably supported in suitable bearings 49. The bearings 49 are mounted within a streamlined housing 50 centrally supported in the compressor inlet by spaced radial vanes 51 of the spigot 12. The vanes 51 may be set at an angle of incidence with respect to the axis of the compressor to impart an initial swirl to the air entering the compressor. The direction of this swirl is counter to the direction of rotation of the rotor 20 to increase the

efficiency of the initial compression stage. The rear portion of the rotor 20 is suitably supported in the housing 10 or the power plant case by supporting and driving means not shown.

The rotor 20 of the blower carries a plurality of axially spaced rows of impeller blades 25. In accordance with this invention, the blades 25 are hollow and are preferably constructed from relatively thin sheet metal. The blades 25 are closed at their tips except for small vent holes 85, and are provided at their root ends with metal shanks or fittings 24. The vent holes 85 are for the purpose of preventing accumulation of oil within the blades, which might occur over a period of time due to seepage past bearing seals. The fittings 24 are separately formed elements engaged within the root portions of the hollow blades at 27 and secured therein by welding or furnace brazing. The portions of the fittings 24 which project beyond the ends of the blades are reduced in cross section leaving shoulders 23 flush with the root ends of the blades. The reduced tongues of the fittings 24 are passed through correspondingly shaped slots or openings 9 in the wall of the rotor shell. The openings 9 are provided in spaced circumferential rows and are located so that the inwardly projecting fittings are received between the inwardly extending flanges of the adjacent rings 21 and 22. These projecting parts of the fittings 24 are employed as anchor lugs for the blades. Each fitting 24 has a transverse opening 8 receiving a bolt or pin 26. The pins 26 serve to secure the fittings to the adjacent rings 21 and 22. The parts are related so that the shoulders 23 at the root ends of the blades 25 engage and conform to the external surface of the rotor 20 when the pins 26 are engaged in their openings 8 to fix the blades to the mounting rings. With this mode of attaching the blades 25 the pairs of hoops or rings 21 and 22 carry the concentrated centrifugal forces of the blades, relieving the shell of the major loads so that the shell may be fabricated from relatively thin light sheet metal for minimum weight. Furthermore, the blade attaching means assures uniform spacing of the blades and facilitates fabrication by mass production methods.

In the form of construction illustrated in Figures 1, 2 and 3, the root fittings 24 are ported or provided with passages to maintain the interiors of their respective blades 25 in communication with the internal cavity of the hollow rotor 20. Thus, as shown in Figure 3, the shank fitting 24 has a pair of ducts 29 and 30 leading from the interior of the respective blade 25 to the interior of the hollow rotor. The blades 25 of the several forward rows of blading are designed to provide for the circulation air therethrough, thereby effecting boundary layer control action for the blades. It is contemplated that boundary layer control apertures or slots of various configurations and in different locations may be provided in the blades. However, the invention provides an improved arrangement of slots for effecting a most efficient boundary layer control action throughout substantially the entire lengths of the blades.

The bodies of the blades 25 in the several forward rows are each provided with a plurality of relatively narrow longitudinally extending slots 31 to 34. The slots 31 to 34 are provided in the convex or anti-lift walls of the blades in or adjacent the chordwise portion of maximum thickness. As shown in Figures 4 and 5, the substantially airfoil-shaped blades 25 are designed so

that their portions of maximum thickness are forward of the medial axial planes, and the slots 31 to 34 are adjacent to but spaced rearwardly from the leading edges. The slots are arranged in rows extending lengthwise of the blades, and there are preferably at least two spaced substantially parallel rows of slots in each blade. The rows of slots extend substantially the entire lengths of the blades and the slots in the adjacent rows are in staggered relation. This spaced staggered relationship of the slots permits slotting of the blade walls throughout practically the entire lengths of the blades without materially weakening the blades or lessening their rigidity.

The number of forward rows of impeller blades 25 provided with slots 31 to 34 as just described, will vary in blowers intended to function under different operating conditions. In most instances it will be found sufficient to provide the slots in the three or four initial rows of blading. Figure 1 shows the three forward rows of blades 25 provided with the slots 31 to 34, it being understood that this is merely typical. It is preferred that the slots in certain rows be forwardly directed for the inspiration or the reception of air, while the slots of other rows be rearwardly directed for the discharge or expiration of air. Where there are three rows of slotted blades, as illustrated, it is preferred to make the slots in the two rearward rows forwardly directed for the reception or influx of air and to make the slots in the forward row, rearwardly directed for the discharge or efflux of the air. The blade walls at the forwardly directed slots 31 to 34 may have internal lips 7 while the blade walls at the rearwardly directed slots 31 to 34 may have internal lips 6, the lips 6 and 7 serving to assist in directing the air and to give the slots a substantially nozzle shape. As above described, the ducts 29 and 30 in the blade root fittings 24, maintain the interiors of the blades 25 in communication with the internal cavity of the hollow rotor 20 so that the air received by the slots of the said two rearward rows of blades enters the interior of the rotor and passes forwardly therein to the forward row of blades for discharge from the slots thereof. Thus the cavity of the hollow rotor 20 forms a common means of communication between the interiors of the several rows of hollow blades. With this simple construction, the slotted blades are maintained in communication with one another without the necessity of providing special ducts or passages.

The invention provides means for distributing air flow through the slotted blades to obtain a balanced or desired boundary layer control effect at the blades of the several rows. It is contemplated that the width or capacity of the slots 31 to 34 of slotted blading rows be related to obtain the desired proportionate or balanced boundary layer control action, or the ducts 29 and 30 of the several blading rows may be proportioned in so far as capacity is concerned to balance the air flow through the several rows. Furthermore, the capacity of both the slots and the ducts may be controlled or related to bring about a preferred relationship of air flow. Unless such provision is made for a distributed flow of boundary layer control air there may be a substantially neutral condition in the intermediate row or rows of slotted blades, with little or no air flow therethrough. I have found it desirable to employ the root ducts 29 and 30 as metering passages. For example, the ducts 29 and 30 of certain blading rows are constricted with relation to the ducts of the other

rows. Thus, where there are three rows of slotted blades as illustrated, the root ducts 29 and 30 of the blades in the third or rearward row are constricted to bring about a substantially balanced or equalized air flow through the second and third rows of blades. Air will flow into the second and third rows of blades and pass out through the initial row of blades.

A plurality of rows of radial inwardly extending diffuser or countervanes 58 is provided on the inside of the housing 10. The stationary vanes 58 are arranged to stand with small clearance between the impeller blades 25 of the rotor 20.

Figures 6 and 7 illustrate another form of rotor construction and blade attachment of the invention. In this case the rotor shell 20a may be a simple thin walled sheet metal member of the desired configuration as in the previously described embodiment. Axially spaced rings 70 are provided on the internal surface of the shell 20 to reinforce the same and to carry the rows of blades 72.

The rings 70 correspond in function to the above described rings 21 and 22 and are suitably fixed to the rotor shell 20a by riveting, spot welding, brazing or the like. However, in this case there is a single ring 70 at each row of impeller blades 72 and each ring 70 is somewhat channel-shaped in transverse cross section having two spaced flanges 71 which project inwardly toward the axis of rotation of the rotor. The hoops or rings 70 have a wall thickness at the wall of the shell 20a approximately the same as the thickness of the shell wall to facilitate the welding or securing of the rings to the shell. The flanges 71 are provided at their inner or opposing sides with shoulders 74. The shoulders 74 of the sets of flanges 71 are directly opposite or in common plane and face inwardly toward the axis of rotation of the rotor. The rings 70 are further provided with circumferentially spaced radial openings 73 for receiving the shanks of the blades 72. The openings 73 are centrally spaced between the sides of the rings 70 to join their channels and have radially outward facing seats 75. The seats 75 are flat and perpendicular to the axes of the openings 73 but have fillets or radii where they join the openings 73. Openings 76 are formed in the wall of the rotor shell 20a to register with the seats 75 and to be coaxial with the openings 73. The openings 73 and 76 and the seats 75 are round or cylindrical and are equally spaced about the circumference of the rotor 20a in accordance with the precalculated location of the blades 72.

The blades 72 may be of the same general construction as the blades 25 described above, being hollow formed sheet metal elements of the required configuration. Each blade 72 is provided with a separately constructed shank fitting having a shank 77 for engaging in an opening 73, and an intermediate circular or cylindrical head 78 for reception in an opening 76 and for engaging a seat 75 and a transverse tongue 79 to be secured in a blade. The shanks 77 are cylindrical to conform with the openings 73 of the rings 70 and their inner ends are adjacent the shoulders 74 of the rings. The heads 78 are flange-like parts presenting flat inner surfaces for cooperating with the seats 75 to establish the perpendicularity of the blades with respect to the rotor. The tongues 79 of the shank fittings are shaped to conform to the internal configuration of the blades 72 and in the construc-

tion illustrated are substantially airfoil shaped to correspond with the blade shape. The shank fittings are preferably precision castings in which case the tongues 79 require no machining and the shanks 77 and heads 78 need only slight machining. The hollow blades 72 are securely fixed or bonded to the tongues 79 of their shank fittings, for example the blades and tongues may be furnace bonded. Thus the shear areas of the blade assemblies are securely joined to dependably withstand the operational loading. In practice it may be found advantageous to construct the blades 72 and the shank fittings, or at least the tongues 79 of the fittings, of the same material to assure a good bonding of blades and tongues. The inner end or base surfaces of the blades 72 and their tongues 79 are ground or otherwise machined to substantially fit the external surface of the rotor shell 20a.

The blades 72 are secured to the rotor assembly by cap screws 80 screwed into bores in the inner ends of the shanks 77 so that their heads cooperate with the above described shoulders 74. It is preferred to arrange washers 81 between the shoulders 74 and the heads of the cap screws 80. It will be seen that when the blades 72 have been set at the proper angle, the screws 80 may be tightened down to secure the blades in position. The cap screws 80 may be locked in place by safety wires 82. Pins 86 may engage in openings in the rings 70 and shank fitting heads 78 to preserve the angular setting of the blades 72. The cap screws 80 are preferably tubular and where desired or necessary, ports or air passages 83 extend through the tongues 79 and heads 78 to communicate with the tubular screws so that the interiors of the blades 72 and rotor shell 20a are connected for the circulation of boundary layer air as in the previously described form of the invention.

From the foregoing it will be seen that I have provided a blower or compressor rotor construction that is extremely simple and inexpensive to manufacture and that is light in weight. The exceptionally small weight of the rotor well suits it for embodiment in aircraft power plants and, of course, minimizes centrifugal forces and inertia effects. While the construction is light in weight, the reinforcing hoops or rings 21 and 22 or 70, dependably carry the impeller blading and maintain the circularity and effective diameter of the rotor during operation.

Having described only typical preferred embodiments of the invention I do not wish to be limited to the specific details set forth but wish to reserve to myself any features or modifications that may fall within the scope of the following claims.

I claim as my invention:

1. In a fluid machine, a housing, a hollow rotor within the housing, a plurality of rows of hollow blades projecting from the rotor and having fluid apertures in their walls, the interiors of the blades being in communication with the internal cavity of the hollow rotor so that fluid may flow from one blade to another through said cavity, and means for restricting the flow through the blades of certain rows to substantially equalize the flow through the blades of the several rows.

2. An axial blower comprising a housing, a rotor in the housing including a hollow thin walled shell, and internal hoops reinforcing the shell, hollow impeller blades projecting from the shell and anchored to said hoops, the blades having communication with the interior of the shell, and

means for producing air flow through the shell and blades.

3. An axial blower comprising a housing, a rotor in the housing including a hollow shell, and axially spaced reinforcing hoops on the interior of the shell, circumferential rows of apertured impeller blades secured to said hoops and projecting from the rotor, and means for producing an air flow through the apertured blades and the hollow shell.

4. A rotor for an axial blower comprising a hollow rotor shell, internal reinforcing hoops for the shell, hollow blades for projecting from the rotor, and fittings secured to the roots of the blades and attached to said hoops to mount the blades on the rotor.

5. A rotor for an axial blower comprising a thin walled hollow rotor shell, internal reinforcing hoops on the wall of the shell, hollow blades for projecting from the rotor, fittings fixed in the root portions of the hollow blades, and means for securing the fittings to said hoops to attach the blades to the rotor.

6. A rotor for an axial blower comprising a hollow rotor shell, internal reinforcing hoops for the shell, the hoops having inwardly projecting circumferential flanges, blades for projecting from the rotor, root parts on the blades received between said flanges, and means for attaching said parts to the flanges to secure the blades to the rotor.

7. A rotor for an axial blower comprising a hollow rotor shell, internal reinforcing hoops for the shell, the hoops having inwardly projecting circumferential flanges, blades for projecting from the rotor, root parts on the blades received between said flanges, and means for attaching said parts to the flanges to secure the blades to the rotor, including pins received in axial openings in the flanges and parts.

8. A rotor for an axial blower comprising a hollow rotor shell, internal reinforcing hoops for the shell, hollow blades for projecting from the rotor, root fittings brazed in the hollow blades, and means for securing the fittings to said hoops.

9. A rotor for an axial blower comprising a hollow rotor shell, internal reinforcing hoops for the shell, hollow blades for projecting from the rotor, fittings projecting from the root ends of the blades and secured to said hoops, there being ducts in the fittings placing the interiors of the blades in communication with the interior of the shell and boundary layer slots in the blades arranged to cause the flow of air through the blades and the interior of the shell.

10. A rotor for an axial blower comprising a hollow rotor shell, internal reinforcing hoops for the shell, hollow blades for projecting from the rotor, fittings projecting from the root ends of the blades and secured to said hoops, there being ducts in the fittings placing the interiors of the blades in communication with the interior of the shell and boundary layer slots in the blades arranged to cause the flow of air through the blades and the interior of the shell, said ducts of certain blade fittings being restricted to meter the flow of air through such blades.

11. A rotor for an axial blower comprising a hollow rotor shell, internal hoops on the wall of the shell, hollow blades for projecting from the rotor, fittings projecting from the root ends of the blades and secured to said hoops, there being ducts in the fittings placing the interiors of the blades in communication with the interior of the shell and boundary layer slots in the blades, said

slots of downstream blades being forwardly directed for the influx of air and the slots of upstream blade being rearwardly directed for the efflux of air, the pressure gradient in the housing causing air flow through the slots, blades, and shell.

12. A rotor for an axial blower comprising a thin-walled light weight hollow shell having rows of circumferentially spaced openings, circumferential internal stiffening rings on the shell, and hollow blades secured to the rings and extending through said openings to project from the shell, the assembly of the shell, rings, and blades constituting a structure having great flexural rigidity and minimum inertia.

13. In an axial compressor, a hollow sheet metal rotor shell having a row of circumferentially spaced openings, a ring secured to the interior of the shell at said row of openings to reinforce the shell, a row of blades at the exterior of the shell, and shanks on the blades extending through said openings and secured to said ring to mount the blades on the rotor.

14. A compressor rotor comprising a hollow sheet metal rotor shell having axially spaced rows of circumferentially spaced openings, rings secured to the interior of the shell at said rows of openings to reinforce the shell, rows of circumferentially spaced blades at the exterior of the shell, shanks on the blades extending through said openings, and means securing the shanks to said rings to attach the blades to the rotor.

15. A compressor rotor comprising a thin-walled rotor shell of generally tubular form having at least one row of circumferentially spaced openings in its peripheral wall, a reinforcing ring secured to the interior of the shell at said row of openings, a row of hollow blades at the exterior of the shell, shank fittings bonded to the interiors of the blades and extending into said openings, and means for securing said fittings to the ring to attach the blades to the rotor.

16. A compressor rotor comprising a thin-walled rotor shell of generally tubular form having at least one row of circumferentially spaced openings in its peripheral wall, a reinforcing ring secured to the interior of the shell at said row of openings, a row of hollow blades at the exterior of the shell, shanks extending into said openings, parts on the shanks conforming to and bonded with the interiors of the blades, and means for securing the shanks to said ring.

17. A compressor rotor comprising a thin-walled rotor shell, a reinforcing ring on the shell, a row of hollow blades for the rotor, shanks for the blades including tongues conforming to and bonded with the interiors of the blades, and means for securing the shanks to said ring.

18. A compressor rotor comprising a thin-walled shell, a reinforcing ring secured within the shell to reinforce the same, there being a row of openings passing through the wall of the shell and said ring, a row of blades at the exterior of the shell, shanks projecting from the root ends of the blades and received in said openings, and screw threaded means securing the shanks to the ring.

19. A compressor rotor comprising a thin-walled shell, a reinforcing ring secured within the shell to reinforce the same, there being a row of openings passing through the wall of the shell and said ring, outwardly facing seats on the ring at the openings, a row of blades at the exterior of the shell, shanks on the blades received

in said openings, parts on the shanks bearing inwardly against said seats, and screws threaded into the shanks and clamping outwardly against the ring to secure the blades to the ring.

5 20. A compressor rotor comprising a thin-walled rotor shell, a thin-walled reinforcing ring secured to the interior of the shell, there being a row of openings passing substantially radially through the wall of the shell and ring, a row of hollow blades at the exterior of the shell, shanks received in said openings, parts on the shanks conforming to and bonded with the interiors of the blades, and screws threaded into the shanks to cooperate with the ring to secure the blades thereto, the shanks and screws having passages for placing the interiors of the blades in communication with the interior of the shell.

10 21. A compressor rotor comprising a thin-walled shell, a reinforcing ring secured within the shell to reinforce the same, there being a row of openings passing through the wall of the shell and said ring, outwardly facing seats on the ring at the openings, a row of blades at the exterior of the shell, shanks on the blades received in said openings, parts on the shanks bearing inwardly against said seats, pins engaged in openings in the seats and said parts to maintain the angular setting of the blades, and screws threaded into the shanks and clamping outwardly against the ring to secure the blades to the ring.

15 22. A compressor rotor comprising a thin-walled rotor shell of generally tubular form having at least one row of circumferentially spaced openings in its peripheral wall, a reinforcing ring secured to the interior of the shell at said row of openings, a row of hollow sheet metal blades at the exterior of the shell, precision-cast shank fittings extending into said openings and having parts conforming to and bonded with the interiors of the blades, and means for securing the fittings to the blades.

20 23. In an axial compressor, a hollow sheet metal rotor shell having a row of circumferentially spaced openings, a ring secured to the interior of the shell at said row of openings to reinforce the shell, the ring having a peripheral flange of approximately the same thickness as the shell wall engaging thereagainst and secured thereto, a row of blades at the exterior of the shell, and shanks on the blades extending through said openings and secured to said ring to mount the blades on the rotor.
